UNITED STATES PATENT OFFICE

WILLIAM A. CHRYST, OF DAYTON, OHIO, ASSIGNOR, BY MESNE ASSIGNMENTS, TO DELCO-REMY CORPORATION, OF DAYTON, OHIO, A CORPORATION OF DELAWARE

ENGINE-STARTING APPARATUS

Application filed November 19, 1926. Serial No. 149,499.

This invention relates to apparatus for starting internal combustion engines and particularly to the type of engine starting apparatus which comprises an electric motor, means for connecting the motor with the engine and including a pinion movable into mesh with a gear connected with the engine and provisions whereby the pinion will be automatically demeshed from the engine gear. 10 when the engine becomes self-operative, and manually operable means for causing the pinion to mesh with the engine gear and for causing the motor to operate.

One object of the present invention is to minimize wear and breakage of the gear teeth by providing manually operable means of simple and economical construction for moving the pinion axially into engagement with the engine gear and for rotating the pinion in 20 case of gear tooth abutment in order that the pinion may be nearly fully meshed with the engine gear before the motor is operated.

A further object is to provide novel means for bringing the motor quickly to rest after 25 a starting operation has been performed in order that, when the engine makes a false start and the pinion is demeshed, the starting operation may be repeated almost immediately without requiring the operator to wait a 30 substantial period for the pinion to come to rest.

Another object of the invention is to prevent entrance of dirt and other foreign substances into the housing of the starting apparatus through an opening in the housing, provided for receiving a manually operable member which moves the pinion into mesh 35 with the engine gear.

Further objects and advantages of the present invention will be apparent from the following description, reference being had to the accompanying drawings wherein a preferred embodiment of one form of the present invention is clearly shown.

45 In the drawings:

Fig. 1 is a fragmentary side view partly in section of engine starting apparatus embodying the present invention, this view showing the apparatus in normal or non-operating 50 position;

Fig. 2 is a sectional view on the line 2-2 of Fig. 1;

Fig. 3 is a view similar to Fig. 1 showing the apparatus after the pinion is nearly in full mesh with the engine gear and at the 55 instant of closing the motor switch; and

Fig. 4 is a view similar to Fig. 3 showing the apparatus after the pinion has been automatically demeshed from the engine gear and before the motor switch has been opened. 60

Referring to the drawings, 20 designates the housing of an electric motor having an armature 21 mounted on a shaft 22, having a helically splined portion 23 which supports a pinion 24 which is helically broached so 65 that it may be movable axially along the shaft 22 and be driven thereby. The shaft 22 is attached screw-threadedly to a shaft journal member 25 having a flange 26 engageable with the pinion 24 and with a surface 27 provided 70 by a housing 28 which is attached to the motor frame 20. The housing 28 provides a bearing 30 for the shaft journal 25. A plate 31, which is attached to the housing 28 by screws 32 separates the chamber within the 75 housing from the space within the motor frame 20 and carries a bearing 33 for supporting an intermediate portion of the shaft 22. The right end of the shaft 22 as viewed in Fig. 1 is supported by a bearing (not 80 shown) carried by an end frame (not shown) attached to the right hand end of the motor frame 20.

As shown in Fig. 3, a portion of the housing 28 extends within the engine flywheel 85 housing 35 which encloses an engine flywheel gear 36 with which the pinion 24 is adapted to mesh. The housing 28 is provided with an opening 37 for receiving a portion of the flywheel gear. The housing 28 provides a cover 90 for the opening through the flywheel housing 35 which receives a portion of the housing 28. The top wall of the housing 28 is provided with an opening 39 for receiving a pedally operable lever 40 which cooperates 95 with means to be described within the housing for moving the pinion into mesh with the engine gear. The lever 40 is provided with a hub 41 which is located within the opening 39 which is supported by a stub shaft 100

42 having a head 43, a portion 44 of lesser diameter than the head 43, a lever bearing portion 45, a portion 46 of still smaller diameter passing through the housing 28 and a threaded portion 47 of still smaller diameter which cooperates with a nut 48 to clamp the shaft 42 against the housing 28, as shown in Fig. 2. In order to prevent entrance of dirt and other foreign substances from the exterior through the opening 39, a cylindrical tubular member 50 is provided. This member is notched at 51 and 52 to receive the arms of the lever 40; and portions 28^a, 28^b and 28^c of the housing 28 are cylindrically machined coaxially with the shaft 42, so that, as the member 50 turns with the lever, its outer cylindrical surface will fit snugly against the surfaces 28^a, 28^b and 28^c. As shown in Fig. 2 the member 50 is provided with an inwardly extending annular flange 53 bearing upon the shaft portion 44 and confined between the shaft head 43 and a ring 54 spacing the lever hub 41 from the flange 53. The flange 53 tends to prevent entrance of dirt endwise of the shaft 42 into the opening 39. Thus in the different positions of the lever (which will be described later) the opening 39 will be substantially closed to prevent the entrance of dirt and other foreign substances into the housing 28.

The lever is operated by a pedal 60 passing through a cup shaped member 61 adapted to be attached to the floor board 62 of an automotive vehicle. A spring 63 tends to maintain the lever 40 and parts connected therewith in normal or non-operating position shown in Fig. 1.

The motor is controlled by a switch contained within a switch case 64 attached to the motor frame 20. The switch is closed by the downward movement of a switch plunger 65 from the position shown in Fig. 1 to that shown in Figs. 3 and 4. The switch is normally maintained open by spring 66 located between the switch case and a cap 67 attached to the plunger 65. The plunger 65 is located in the path of movement of an extension 68 of the lever 40.

The lower arm of the lever 40 carries a stud 70 received by a helical slot 71 provided by a cylindrical sleeve 72. The end of the sleeve furthest from the pinion 24 or the right hand end as viewed in Fig. 1 is attached to a disc 73 supported by a hub 74 slidable along the shaft 22. The end of the sleeve 72 nearest the pinion 24 is divided by slots 75 into resilient clutch elements 76 each provided with a conical surface 77 adapted to engage the internal conical surface 78 of a driven clutch element 79 attached to the pinion 24. The hub 74 carries a plate 80 of such external diameter as to be normally out of engagement with the clutch element 76 when these elements are out of wedging engagement with the clutch 79. By this construc-

tion the driving clutch elements 76 adapt themselves to fit drivingly with the driven clutch 79. The plate 80 limits the amount of wedging between the clutch elements so that unclutching may take place readily when the motor begins to operate.

The helical slot 71 in the sleeve 72 is variable in pitch or lead, the portion of smallest lead normally receiving the stud 70 as shown in Fig. 1. This construction and arrangement is desirable so that, initially, the tendency of the sleeve to move endwise from non-operating position toward gear meshing position is greater than the tendency to rotate.

To start the engine the operator will depress the pedal 60, thereby causing the lever 40 to move clockwise from the position shown in Fig. 1 to the position shown in Fig. 3. The pin 70 will be moved longitudinally of the sleeve 72 to cause the latter to move toward the left in the drawings so that the clutch members 76 will be moved axially into engagement with the clutch surface 78 of the driven clutch 79. Following this, the pinion 24 will be moved into engagement with the engine gear 36. If motion of the pinion 24 is not arrested by gear tooth abutment, pinion 24 will be moved nearly into full mesh with the engine gear with relatively little rotation of the sleeve 72 having taken place. Then the motor switch is closed and the motor will thread the pinion into full mesh with the engine gear and against the stop flange 26. Following this, the pinion will rotate with the shaft 22 to crank the engine.

When the engine becomes self-operative, the pinion 24 will be automatically demeshed from the engine gear 36. The shifting sleeve 72 and the pinion 24 will therefore be returned to the position shown in Fig. 4, although the operator should fail to release the pedal 60. When pedal 60 is released, the spring 63 will move the lever 40 from the position shown in Fig. 4 to that shown in Fig. 1, thereby causing the sleeve 72 to be rotated into the position shown in Fig. 1. During the return of the pedal 60 the spring 66 will move the switch plunger 65 to switch open position.

In case the teeth of the pinion 24 should abut the teeth of the gear 36 during downward motion of the pedal 60, the driving clutch members 76 will be wedged firmly into engagement with the driven clutch 79 and the sleeve 72 will be rotated in order to rotate the pinion 24 through the clutch elements so that the pinion will be brought into meshing registration with the gear 36. As previously described, the pinion will be moved nearly into full mesh with the engine gear before the motor is operated. As the pinion is moved against the stop flange 26, the clutch

element 79 will be disengaged from the clutch elements 76.

The motor shaft 22 is brought quickly to rest after the pedal 60 has been released by braking means including a brake disc 90 connected with the shaft 22, a floating brake disc 91 and a non-rotatable brake disc 92. The disc 92 is supported by one or more studs 93 which extend through suitable holes in the plate 31 and are adapted to be engaged by the disc 73. It is apparent that the spring 63 when relieved will cause the lever 40 to move counter-clockwise and the plate 73 to be urged against the studs 93, thereby causing the stationary brake disc 92 to be urged toward the discs 91 and 90. Therefore this invention provides a brake of simple and compact construction for bringing the motor quickly to rest after a starting operation has been performed, so that, in case of a false start, the starting operation can be repeated almost immediately after the pedal has been released, without liability of damage to the teeth of the gearing.

25 In case of back-fire before the meshing operation has been completed, the driven clutch member 79 will slip relative to the driving clutch member 76 to permit rotation of the pinion relative to the sleeve 72.

30 While the form of embodiment of the present invention as herein disclosed, constitutes a preferred form, it is to be understood that other forms might be adopted, all coming within the scope of the claims which follow.

35 What is claimed is as follows:

1. Engine starting apparatus comprising, a motor; means for connecting the motor with the gear of an engine to be started and including a pinion slidable into mesh with the engine gear and including provisions whereby the pinion will be automatically demeshed from the gear when the engine starts; and means for moving the pinion axially into engagement with the gear and for rotating the pinion in case of gear tooth abutment, said means including a driven friction clutch member provided by the pinion, a driving clutch member movable axially into engagement with the driven clutch member, a manually operable member movable longitudinally of the axis of the clutch members, and elements providing a pin-and-slot connection between the manually operable member and the driving clutch member, the slot being oblique to the axis of the clutch members.

2. Engine starting apparatus according to claim 1 in which the driving clutch member is provided by an axially movable sleeve, and the sleeve is provided with a helical slot receiving a pin carried by the manually operable member.

3. Engine starting apparatus according to claim 1 in which the clutch members have conical surfaces which wedgingly cooperate,

one of the clutch members having a plurality of resilient portions which yield under pressure applied to wedge the driving clutch member into driving engagement with the driven clutch member.

4. Engine starting apparatus according to claim 1 in which the driven clutch has a conical surface internally engaged by a plurality of resilient, driving clutch elements of the driving clutch member, each element having a corresponding conical surface, said elements yielding as pressure is applied to wedge the driving clutch member into driving engagement with the driven clutch member.

5. Engine starting apparatus according to claim 1, in which the driven clutch has a conical surface, and in which the driving clutch is provided by a sleeve having its end which is furthest from the driven clutch fixed to a hub which is axially slid able, and having its end which is adjacent the driven clutch slotted to provide a plurality of resilient clutch elements each having a conical clutch surface adapted to engage the conical surface of the driven clutch.

6. Engine starting apparatus comprising, a motor, a shaft operated thereby, a bearing supporting the shaft intermediate its ends, a bearing supporting wall, a brake disc attached to the shaft beyond one side of the wall, a second brake disc located between the wall and first brake disc, a pinion located beyond the other side of said wall and driv ingly connected with the shaft and movable away from said wall into engagement with the gear of an engine to be started, a member located between the pinion and wall for moving the pinion, and a member extending through an opening in the wall and connected with the second mentioned brake disc and engaged by the pinion moving member when returned to nonoperating position.

7. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; and manually operable means for shifting the pinion endwise into mesh with the engine gear and for rotating the pinion in case the pinion teeth collide with the engine gear teeth, said means including two members movable along the shaft, one of said members being rotatable and having a part located oblique to the direction of bodily motion of said members and engaged by the other member whereby the rotatable, manually operable member may be rotated by the other member when moved along the shaft,

and a friction clutch for connecting the rotatable member with the pinion.

8. An engine starter drive comprising, in combination, a rotatable drive connecting member movable axially into driving relation with a rotatable part of the engine to be started; automatic means for disconnecting the drive connecting member from the engine part when the engine starts; and a manually operable device for moving the drive connecting member into driving engagement with the engine part; said device including two members one of which is rotatable coaxially of the drive connecting member, a friction clutch for connecting the drive connecting member with the rotatable manually operable member, and means for connecting the manually operable members for endwise movement together, or so that endwise movement of one member relative to the other will effect rotation of the rotatable, manually operable member.

9. An engine starter drive comprising, in combination, a rotatable drive connecting member movable axially into driving relation with a rotatable part of the engine to be started; automatic means for disconnecting the drive connecting member from the engine part when the engine starts; and a manually operable device for moving the drive connecting member into driving engagement with the engine part; said device including a member rotatable coaxially of the drive connecting member and movable axially into engagement with the drive connecting member, a friction clutch for rotatively connecting said members, a manually operable part movable along the rotatable, manually operable member, and means for connecting the manually operable part and member so that they may move together and so that, in case axial movement of the rotatable manually operable member is arrested, further movement of the manually operable part will effect rotation of the manually operable member.

10. An engine starter drive comprising, in combination, a rotatable drive connecting member movable axially into driving relation with a rotatable part of the engine to be started; automatic means for disconnecting the drive connecting member from the engine part when the engine starts; and a manually operable device for moving the drive connecting member into driving engagement with the engine part; said device including two elements adapted to move in the direction of movement of the drive connecting member when approaching the engine part, one of said elements being rotatable coaxially of the drive connecting member and engageable with said member, a friction clutch for rotatively connecting the rotatable element and drive connecting member, and means for connecting the elements so that,

when the rotatable element is moved axially by the other manually operable element, the rotatable element tends to rotate, and means tending initially to resist rotation of the rotatable manually operable element.

In testimony whereof I hereto affix my signature.

WILLIAM A. CHRYST.
